UNITED STATES PATENT OFFICE.

FRANKLIN N. ROPP, OF LOS ANGELES, CALIFORNIA.

JOIST HANGER.

Application filed September 12, 1927. Serial No. 218,980.

This invention relates to joist hangers, and the main object is to provide an improved type of hanger adapted for use in the construction of concrete buildings, and of the same general type as that shown in my application for patent filed April 30, 1927, Serial Number 187,786, but embodying improvements thereover.

Another object is to provide an integral or composite hanger formed of sheet metal and provided with a U-shaped position for receiving and holding an end of the joist abutting the face of the wall, and an inwardly and upwardly inclined member adapted to be embedded in the concrete of a wall and disposed at such an angle that the wall may properly support the joist and the hanger without undue strain, and providing an ample safety factor.

Other objects will appear as the description progresses.

I have shown a preferred embodiment of my invention in the accompanying drawings, in which:

Fig. 1 is a perspective view of a hanger embodying my improvements;

Fig. 2 is a perspective view of a section of concrete wall with my hanger mounted therein and serving as supports for joists.

My improvements consists primarily in the provision of an integral or composite hanger formed of sheet metal and embodying a U-shaped hanger proper H, having parallel upwardly extending sides A and A' spaced apart and connected at the bottom by a portion B. The sides A and A' have inwardly and upwardly extending portions a and a', respectively, which may be formed as shown in Fig. 1, or otherwise, for permanently anchoring the hangers in the concrete as shown in Fig. 2.

The rear edges b and b' of the sides A and A', respectively, are adapted to rest against the front face of the concrete wall W, and are arranged to support joists as at J, J, on the bottom B and between the sides A and A'. The upper portion of the hanger is provided with an angularly disposed extension C having a lower end D, which may be welded to the lower edges of the portions a and a' at points d and d', etc., where the hanger is of composite character.

Portion C has a central portion C' extending upwardly and inwardly into the wall W at an acute angle, and is bent upwardly and forwardly at E to form an anchor.

When the hanger H is embodied in the wall as shown, it provides a rigid and firm brack-

et support for an end of the joist as at J, with the joist resting at its end against the face of the wall W. Such a type of hanger may be readily built into the wall W during the erection of a building, as shown in Fig. 2, where forms F and F' are used for providing the wall recess into which the concrete for the wall W is poured.

The boards of the forms F are cut away to provide recesses into which the joists J, J, etc., are framed as the forms are erected, so that the ends of the joists will abut the front face of the wall. As the forms are erected studs S, S, etc., are arranged on the inner side of the form F and carry a plate P on the tops thereon, on which the hangers H are set, and to which said hangers may be temporarily nailed in one or more openings as at 10 in the bottoms B of the hangers, so as to properly position the hangers with respect to the forms of the wall while the concrete of the wall is being poured.

When the wall is erected to a point above the plane of the joists J, J, etc., the joists may be placed in the hangers H and secured thereto by nails inserted through apertures 12, 12 in the sides A and A'. Thus the joists of a building may be set into place as the wall is erected, and the studs S and plates P may be arranged in tiers one upon the other, if the building has more than two floors.

The form of the hangers as shown is particularly arranged so that when the edges b and b' of the hangers rest against the completed wall, and the portion C thereof is embedded in the concrete of the wall, the hangers provide a substantially rigid structure which can not be removed from position due to any strain or loads on the joists.

Furthermore, the placing of the hangers in the wall does not require intricate or complicated framing of the forms and structure necessary for the erection of the wall. Accordingly, a substantial amount of time and money is saved over other methods and devices.

It will be understood that while I have shown a preferred embodiment of my invention, the same may be modified or changed within the scope of the appended claims without departing from the spirit thereof.

What I claim is:

1. A joist hanger comprising a stirrup having vertically disposed parallel sides, a bottom portion connecting said sides, the inner edges of said sides and said bottom portion adapted to abut the face of a wall, extensions

integral with and having their lower edges disposed at right angles to said sides, and an anchor member extended horizontally, thence inclined upwardly and bent forwardly at its 5 end from and secured to said extensions, said extensions and said anchor member adapted to be embedded in the wall, for the purpose described.

2. A joist hanger comprising a U-shaped 10 stirrup having right angularly disposed edge portions adapted to abut the face of and to rest upon seats in a wall, and an anchor member extended horizontally from said stirrup and inclined upwardly and bent forwardly 15 at its inner end whereby when the same is embedded in a wall said hanger will be permanently supported, as and for the purpose described.

3. A hanger comprising a U-shaped stirrup 20 for receiving a joist, an anchor having an outer horizontal supporting portion perma-

nently secured to the upper portion of said stirrup, and a central portion inclined inwardly and upwardly from the stirrup and bent forwardly at its inner end to form an anchor 25 when the same is embedded in a wall.

4. A joint hanger comprising a U-shaped stirrup having spaced parallel side portions adapted to be disposed edgewise against the face of a wall and a connecting portion for 30 supporting a joist, said sides having their upper portions extended inwardly from the rear edges of the lower portions thereof so as to be embedded in a wall, and an anchor member having a horizontal portion connecting 35 the lower edges of the upper portions of said sides and bent upwardly and inwardly therefrom at an acute angle and thence forwardly at a point above the upper extremities of said sides, for the purpose described.

FRANKLIN N. ROPP.
